ATTORNEYS

Patented Oct. 30, 1923.

UNITED STATES PATENT OFFICE.

AUGUSTUS D. CURTIS, OF CHICAGO, ILLINOIS.

LIGHTING FIXTURE.

Application filed September 17, 1921. Serial No. 501,265.

To all whom it may concern:

Be it known that I, AUGUSTUS D. CURTIS, a citizen of the United States, residing at Chicago, in the county of Cook and State 5 of Illinois, have invented certain new and useful Improvements in Lighting Fixtures, of which the following is a specification.

This invention relates generally to illumination and particularly to improvements 10 in lighting fixtures.

The general purpose of the invention is the provision of a decorative lighting fixture having certain desirable qualities as to the diffusion and modification of light and including features of construction which facilitate its installation, its maintenance in proper working order and its adaptation to different conditions or requirements of use.

A more specific object of the invention is 20 the provision of improvements in the structure of a lighting fixture designed to direct a certain amount of light from a contained source directly over a limited and intended area, to diffuse a certain other modicum of light from the source and render it available 25 for general illumination of the room indirectly, and to modify through the instrumentality of proper modifying screens a third portion of the light from the source 30 and diffuse it directly and indirectly about the directly illuminated area.

A more specific object of the invention is 35 the provision of a lighting fixture applicable particularly as a fixture for dining rooms and arranged so as to illuminate the top of a table placed beneath the fixture directly with relatively bright light, to modify the portion of the light which is directed beyond the area of the table so as to render 40 it soft and diffused, and to secure a desired general illumination of the room through the diffusion of light indirectly or by reflection from the ceiling.

Another particular object of the invention 45 is the provision of such a fixture having a modifying shade portion and a light directing portion both associated with the luminary and cooperating in such relationships that the former may be removed to afford a 50 fixture constituted of the light directing portion having certain desirable light distributing functions.

Another specific object of the invention is 55 the provision of a lighting fixture which includes a light modifying globe or shade so constructed and arranged in association

with the luminary and its support as to permit the ready detachment of the shade for the purpose of cleaning or substitution without in any manner incapacitating the luminary or its support or requiring any detachment of either.

Another important purpose of the invention is the provision of a lighting fixture susceptible of embodiment in pleasing and ornamental design and effective to conceal the purely mechanical features of the lamp mounting as well as the source of light itself.

Another specific object of the invention is 70 the provision of such a fixture which may be constructed quite economically, and one which may be embodied in a very light construction and at the same time be possessed of the necessary stability and rigidity to 75 withstand contemplated usage and maintain its form and function.

Other and further objects of the invention will be pointed out hereinafter, indicated in 80 the appended claims or obvious upon an understanding of the invention from the present disclosure, reference being had to the accompanying drawing forming a part of this specification. For the purpose of the present disclosure I have shown in the drawing 85 one structural form in which the invention may be embodied, but it is to be understood that the same is here presented for illustrative purpose merely and is not to be accorded the effect of imposing undue or unnecessary limitation upon the scope of the 90 invention as hereinafter claimed, as I know that the invention may be embodied in various other forms and fashions.

In the said drawing,

Fig. 1 is a sectional elevation of a fixture taken on a diameter;

Fig. 2 is a top or plan view;

Fig. 3 is a fragmentary detail illustrating a feature of the mounting of the light 100 directing member;

Fig. 4 is a fragmentary detail in the nature of a part vertical section of the connection between the fixture and the support; 105 and

Fig. 5 is a fragmentary detail in the nature of a side view of an element of the shade mounting.

The nature of the invention will best be understood by reference to these drawings 110 in detail, whence it will be observed that the numeral 1 designates a suitable support,

which may be rigid or pendant and which forms a mounting for a socket 2 of customary construction adapted to constitute an operative connection mounting for an incandescent lamp 4. Adjustably mounted on the support 1, as by means of a set screw 5^a, is a sleeve 5 the lower portion of which is spaced apart from the lamp socket and mounting as illustrated in Fig. 4, to afford 10 an annular channel.

A fixture embodying the subject matter of the present invention includes a suitable frame constituting a support for a light modifying member in the nature of a globe or shade, and a light directing member in the nature of a diffusing screen or reflector. This frame includes in the first place a hanger portion which is here illustrated as including a supporting ring 6 and attaching ring 7 which are connected by radial members 8, all of which may be formed conveniently of metal rods or wires. The supporting ring 6 may be of any desired conformation and of an extent to fulfill the 20 requirements hereinafter specified, while the attaching ring 7 is of suitable size to encompass the socket 2 and fit within the annular channel beneath the sleeve member 5. Suitable attaching means, exemplified by the 25 screws 9, is arranged for securing the hanger member to the support 1. The hanger member constitutes a sustaining support for a light directing member. While the latter may be of various forms, I have illustrated 30 one form now known to the trade, which comprises a bell shaped globe, the lower portion of which, designated by the numeral 10, is transparent or translucent and constitutes a light diffusing screen, and the upper portion of which, designated by the numeral 45 11, is opaque and reflective and flares upwardly and outwardly in a reverse curve or ogee form, and constitutes a light reflecting portion. It may be given this characteristic by having its outer surface silvered to 50 constitute a mirror. This light modifying member is supported on the hanger member in any suitable fashion, the supporting means shown comprising clips 12 secured to 55 the spacer arms 8 and engaging under the upper flared marginal portion of the light directing member. One of these clips is 60 slideable on its supporting arm 8 so as to permit its being withdrawn to enable the 65 dismounting of the light directing member.

The position of the sleeve 5 upon the support 1 is such that the luminant will be positioned approximately at the junction line between the members 10 and 11 or slightly 70 above said line. The hanger member thus forms a mounting for the light directing member whereby it is maintained on the lamp support in proper association with the luminant. With a light directing member 75 of the form shown, which is open at the bot-

tom, a certain amount of light from the luminant will be effective directly upon an area below the lamp, while a second portion of the light will be diffused through the light diffusing portion 10, and a third portion of the light will be impinged upon the light reflecting portion 11 and reflected upwardly at different angles so as to impinge 80 the ceiling, whence it will be reflected to illuminate the room indirectly.

The light modifying member includes a frame comprising an upper ring 14, a lower ring 15, one or more girth rings 16 disposed intermediate the upper and bottom rings and an aperture ring 17. These rings are 85 connected and supported in the desired relationship by a plurality of spacing members 18. The size and shape of the top ring 14 is such as to permit the insertion of the hanger member 8 and the light directing member through it. The size and contour 90 of the aperture ring 17 are approximately such as to register with the bottom aperture or light transmitting portion of the light directing member, while the bottom 95 ring 15 is of somewhat larger diameter than the aperture ring, and the girth rings 16 are more appropriately of still larger diameter. The shape of these rings may be varied as desired to give the light modifying member any intended form. It is contemplated that this form will be such as to permit it to receive entirely within it 100 the lamp and the light directing member. This frame of the light modifying member is covered with suitable translucent material 19 such as fabric, paper or glass which may be supported upon the frame members in any suitable fashion, the areas within the top ring 14 and the aperture ring 17 being 105 left uncovered. In the form illustrated it will be observed that the aperture ring 17 is supported above the bottom ring 15 and within the body of the light modifying member, the covering material between said 110 rings forming a downwardly and outwardly flaring wall portion accommodating the direct transmission of light from the luminant. The light modifying member thus constituted is detachably supported on the 115 hanger member in any suitable or convenient fashion. In the illustrative embodiment I have shown the hanger provided with clips 20 attached to the ring 6 and cooperating therewith to afford slots into 120 which brackets 21 carried on the frame of the light modifying member may be inserted and retained, rotation of the light modifying member being effective to accomplish 125 engagement or disengagement of said brackets with said supporting clips. With the light modifying member thus supported in position on the hanger member, the lamp and the light directing member are entirely housed by the light modifying member, the 130

- area within the aperture ring 17 permitting the unrestricted passage of light directly from the luminant to the intended area beneath it, and the area within the top ring 14 permitting the passage of light upwardly from the luminant and from the reflecting member 11. The diffusing member 10, which may be of prismatic or frosted glass, is effective to diffuse or distribute light 10 against the inner surface of the covering material 19, through which portions of such light will be transmitted to the area about that subject to the direct illumination of light emerging through the aperture ring 15. The arrangement thus will give the light modifying member an illuminated appearance which, through the employment of decorative effects, may be made very attractive and pleasing, and the light transmitted therethrough will be toned and softened. Due to the employment of diffusing member 10 the translucent modifying member will be uniformly illuminated without showing the glare of the lamp directly through it. Objects within the area of the directly transmitted light will be subjected to the bright illumination from the luminant, while the light which is directed upwardly will be diffused over the ceiling and rendered effective to illuminate the room generally in a subdued degree. The fixture is thus particularly adapted, both from features of design to which it is adapted and its illuminating characteristics, to use above 20 tables, as in dining rooms or other installations where a decorative and effective fixture is desired. The top of the table will be well illuminated by the direct rays, and the room illuminated to a modified degree by the reflected rays, while the light transmitted through the light modifying member about the table will be softened and modified so that it will not be trying to the eyes of persons within the area subject to it.
- 5 In addition to these desirable illuminating characteristics of the fixture, it is of particular advantage from a standpoint of maintenance due to the facility with which the light modifying member may be dismounted for the purpose of dusting and the like, and particularly due to the fact that such dismounting does not in any manner interfere with the operation or require the disconnection of the lamp or the light directing member. Thus the likelihood of the intended relationship of the light directing member to the luminant being disarranged by inexperienced persons is practically eliminated. A further valuable feature resides in the lightness of the construction and its low cost, which, in conjunction with the facility for mounting and dismounting the light modifying member particularly adapts the fixture to installations where it 30 may be desired to substitute light modifying members of various and differing designs for different occasions. The fixture also facilitates variation in the illumination of the room such as may be desired to accommodate different uses as, when a high 70 degree of illumination is desired, the light modifying member may be removed, leaving the lamp and the light directing member in cooperative relationship, which members constitute in themselves a slightly and 75 effective light distributing fixture. The structure is particularly adaptable to great variation in design and form of the light modifying member, whereby it is accommodated particularly to decorative effects. 80
- I claim:
1. In a lighting fixture the combination with a lamp support and lamp, of a hanger member mounted on the support above the lamp, a light directing member mounted on the hanger member and depending therefrom in operative association with the lamp, and a light modifying member supported on the hanger member and depending therefrom to encompass the lamp and light directing member; said light modifying member having portions accommodating passage of light directly from the lamp and portions disposed to receive light transmitted by the light directing member. 90
  2. In a lighting fixture the combination with a lamp support and lamp, of a hanger member mounted on the support above the lamp, a light directing member supported on the hanger and depending therefrom in association with the lamp, and a light modifying member mounted on the hanger and substantially enclosing the same and the lamp and light directing member; said light modifying member having translucent wall portions arranged to receive light from the light directing member and also having clear openings arranged to permit passage of light upwardly and downwardly directly from the lamp. 100
  3. In a lighting fixture the combination with a lamp support and lamp, of a hanger mounted on the support above the lamp, a depending light directing member mounted on the hanger in association with the lamp, and a depending light modifying member detachably mounted on the hanger and substantially enclosing the lamp and light directing member, said light modifying member being movable to and from its mounted position without requiring dismounting of the lamp or light directing member. 110
  4. In a lighting fixture the combination with a ceiling lamp support and lamp, of a hanger mounted on the support and positioned above the lamp, a light directing member mounted on the hanger and encompassing the lamp, a light modifying member mounted on the hanger, said light modifying member having a wall portion sub- 120

stantially enclosing the lamp and light directing member and affording top and bottom light transmitting apertures, said modifying member being movable to mounted position over the light directing member and lamp to position said light transmitting apertures in operative relationship to the lamp.

5. In a lighting fixture the combination 10 with a depending lamp support and lamp, of a light directing member supported on the former in operative association with the latter, and a light modifying member encompassing the lamp and directing member, said modifying member affording a bottom light emitting aperture and having an inwardly extending wall portion terminating adjacent the light directing member.

6. In a lighting fixture, in combination, a 20 frame adapted for mounting on a lamp support, a light directing member mounted on said frame and depending therefrom to encompass a lamp on the support, said light directing member having an upper portion 25 adapted to reflect light from the lamp upwardly and a lower light diffusing portion arranged to diffuse light from the lamp laterally, a light modifying member mounted on the frame and enclosing the light directing member, said light modifying member having unobstructed top and bottom apertures and the light directing member having unobstructed top and bottom apertures for emission of light through the said 35 apertures of the light modifying member.

7. In a lighting fixture in combination, a 40 hanger adapted for attachment to a lamp support, a light directing member mounted on said hanger to depend therefrom about a lamp on the support, and a light modifying member having translucent wall portions arranged to encompass the light directing member and top and bottom apertures to permit unobstructed transmission of light 45 from the lamp; said light directing member including a reflector portion disposed to reflect light upwardly through the top aperture of the light modifying member, a light diffusing portion arranged to diffuse light laterally against the wall portion of the 50 light modifying member and a bottom aperture arranged to permit transmission of light through the bottom aperture of the light modifying member.

55. 8. In a lighting fixture, in combination, a hanger adapted for connection to a pendent lamp support, a light directing member mounted on said hanger and depending therefrom in position to encompass a lamp 60 on the support, a light modifying member mounted on the hanger and having translucent wall portions arranged to encompass the light directing member, said light directing member having a reflector portion

arranged to reflect light from the lamp upwardly and a light diffusing portion arranged to diffuse light against the wall portions of the light modifying member, and the light modifying member affording top and bottom apertures arranged to permit 70 passage of light directly from the light directing member.

9. In a lighting fixture, in combination, a hanger adapted for attachment to a lamp support, a light directing member mounted 75 on said hanger in position to encompass a lamp on the support, said light directing member including a reflector portion arranged to reflect light from the lamp toward the support and a light diffusing portion 80 arranged to diffuse light laterally from the lamp, both said reflector and diffusing portions being disposed to encompass portions of the lamp, and a light modifying member movable to and from mounted position on 85 the support independently of the light directing member.

10. A lighting fixture for overhead support comprising in combination, a hanger above the lamp adapted for connection to a 90 lamp support, a light directing member mounted on said hanger and depending therefrom to encompass a lamp on the support, said light directing member having a reflector portion arranged to reflect light 95 from the lamp toward the ceiling and a diffusing portion for diffusing light from the lamp laterally, and a light modifying member detachably mounted on said hanger and 100 movable to and from a position encompassing the light directing member, said light modifying member having translucent wall portions disposed to receive light from said light diffusing portion.

11. In a lighting fixture, in combination, 105 a hanger adapted for connection to a lamp support, a light directing member mounted on said hanger, and a light modifying member mounted on said hanger and encompassing the light directing member, said light 110 modifying member having translucent side wall portions affording an axial bottom aperture and a re-entrant wall portion extending from said side wall portions about said aperture into proximity with the light 115 directing member.

12. In a lighting fixture, in combination, a hanger having radial arms connected by a hoop portion, means for mounting said hanger on a lamp support, a light directing member detachably mounted on said arms in position to encompass a lamp on the support, and a light modifying member detachably mounted on said hoop portion in position to 120 encompass the light directing member.

In testimony whereof I have hereunto signed my name.

AUGUSTUS D. CURTIS.
